UNITED STATES PATENT OFFICE.

WILLIAM ROWLAND EDWARDS, OF LONDON, ENGLAND.

NONSPILLABLE BOX OR CONTAINER.

Application filed July 13, 1923. Serial No. 651,320.

To all whom it may concern:

Be it known that I, WILLIAM ROWLAND EDWARDS, a subject of the King of Great Britain, of 24 Upper Bedford Place, London, England, have invented a certain new and useful Improvement in a Nonspillable Box or Container, Such as Those Used for Electric Accumulators or the like, of which the following is a specification.

10 This invention relates to non-spillable boxes or containers for electric batteries or accumulators, and the invention has for its object to provide an improved means for venting the same.

15 According to the present invention a vent in the top of the box or cell is adapted to be opened and closed by a rod so arranged and fitted as to be pressed upwards and open the vent when the box is resting on its support and to protrude from the bottom of the box and close the vent when the box is raised from its support.

20 The said rod is preferably mounted in a tube passing through the box from top to bottom and is pressed downward by a suitable spring.

25 The vent may either be formed upon the end of the rod or it may be placed to one side of the through tube and rod so as to be opened and closed by a suitable connection from the head of the rod.

30 The accompanying drawings illustrate several ways of carrying out this invention.

35 Fig. 1 is a sectional elevation showing one construction.

40 Fig. 2 is a similar view showing another construction,

45 Figs. 3 and 4 are detail views showing modifications of the construction shown in Fig. 1.

50 Figs. 5 and 6 are sectional elevations showing two further modifications.

55 Fig. 7 is a sectional elevation showing the construction of an outer case for the battery when used for aeroplanes.

In the construction shown in Fig. 1 the box or container *a* is fitted with a straight tube *b* passing through the box from top to bottom, and in this tube is mounted a through rod *c*. In the top of the box *a* at a short distance from the tube *b* and rod *c* I fit another short venting tube *d* which passes into the box and extends a short distance above the top or cover. The upper end of the rod *c* is formed with a head

adapted to bear against a resilient lever or bearer plate *e* of ebonite or other suitable material, the other end of which is fixed to the top of the box as at *f*. The said lever *e* passes over the top of the vent tube *d* and is fitted with a disc of rubber or other suitable material *g* which when pressed down upon the aperture of the vent *d* will close it tightly. The lower end of the rod *c* is pressed downward by the resilient lever *e* so as to protrude from the bottom of the box as shown when the latter is lifted off its support.

The vent tube *d* is coned to prevent the liquid from lodging therein and the upper edges of the said tube are bevelled off to form a good joint with the closing disc *g*.

It will be seen that when the battery box *a* is lifted or tilted the resilient lever *e* will press the through rod *c* downwards so as to protrude from the bottom of the box, and will also keep the rubber disc *g* tightly pressed down on the top of the short vent tube *d* whilst when the box is on the ground the through rod *c* being pressed upwards against the lever *e* the latter will be raised and the rubber disc *g* lifted off the top of the venting tube *d* allowing the escape of fumes from the box.

In the construction shown in Fig. 2, the lower end of the through tube *b* is enlarged to form a recess *b'* in which is mounted a spring *h* surrounding the lower end of the rod *c* and bearing against the end of the recess *b'* at one end whilst the other bears upon an adjustable nut or collar *i* on the lower end of the rod which projects a suitable distance from the recess.

In this construction the upper end of the rod *c* is directly connected to the lever *e*.

In the modification shown in Fig. 3, the lever *e* is held down by a spring *j* which serves to operate the rod *c* and in Fig. 4 the rod *c* passes through the end of the lever *e* and bears against a spring *j'* which surrounds the upper end of the rod and is supported by a bridge piece *k* through which the upper end of the said rod passes.

In the further modified constructions shown in Fig. 5 the venting device is placed in alignment with the rod *c* which slides up and down in the tube *b*.

The rod *c* is enlarged and made tubular at its top end as at *c'* so as to fit closely into a correspondingly enlarged end *b'* of the tube *b*.

- Holes b^3 are made in the tube and corresponding holes c^3 are also made in the tubular end of the rod c the arrangement of which holes is such that when opposite each other there will be a clear passage left for any fumes or gas to pass from inside the battery box to the atmosphere. The top of the said tubular part of the rod is either left open or perforated.
- 10 In the drawing the tube b is shown as extended above the top of the box a and covered by a perforated cap l and the spring h for pressing the rod c downwards is enclosed between the said cap l and the base of 15 the tubular part c' of the rod.
- The rod c may have a collar or washer of suitable material fitted near the top and below the tubular part to prevent any moisture that may accumulate from running down 20 the tube.

In operation, when the box a rests upon its support the rod c is pressed upwards and the holes b^3 and c^3 come opposite each other and a clear opening is left from the inside 25 of the box to the atmosphere and when the box is lifted the spring h will push the rod c downwards. The tubular parts of the rod c will slide endwise in the enlarged end b^2 of the tube b and close the venting holes b^3 30 and thus prevent any liquid or fumes from passing out of the box.

Fig. 6 shows a modification of Fig. 5 wherein the spring h for pressing the rod c downwards is mounted in a recess b' at the 35 lower end of the tube b in a similar manner to Fig. 2, but in this arrangement the upper end of the rod c carries a coned head m seated so as to cover the holes b^3 in a coned recess in the base of the enlargement b^2 at 40 the upper end of tube b thus forming a venting valve head which is opened when the rod c is pressed up and closed when the said rod is moved down by its spring so as to protrude from the base of the box, the 45 operation is otherwise the same as in the other constructions described.

With the arrangements shown in Figs. 5 and 6, the tube b may be filled with vaseline or other lubricating material to facilitate 50 the sliding movement of the rod c which material will also prevent moisture from passing down the tube b .

For use in aeroplanes or where the battery is likely to be used in an inverted position I may employ an outer casing n of 55 suitable material as shown in Fig. 7, the sides and ends of the said outer casing n being inclined outwardly and upwardly so that when the casing is tilted to any considerable angle, the accumulator will also 60 tilt sufficiently as shown in dotted lines to allow the rod c to operate.

The top of the outer case n is suitably 65 ventilated and placed so close to the accumulator as to ensure that the latter always re-

turns to correct position when the case is restored to its original position or for the same purpose bars may be fixed across the top of the said outer case to prevent the accumulator from falling out when in an up-side down position.

The outer case may be screwed to the floor or secured by any other suitable method.

What I claim as my invention and desire to secure by Letters Patent is:—

1. Improved means for venting the boxes or containers for electric batteries or accumulators comprising a vent in the top of the box or cell adapted to be opened and closed through the medium of a rod so arranged and fitted as to be pressed upward and open the vent when the box is resting on its support.

2. Improved means for venting containers for electric batteries comprising the combination with a battery container of a vent in the top thereof, a vertically slideable rod carried by said container and projecting beyond the base thereof, resilient means for pressing said rod downwards and causing the lower end to protrude beyond the bottom of the container, means whereby the said vent is opened by the rod when the protruding end thereof is pressed upward by the container resting on its support and whereby said vent is closed by said rod protruding from the bottom of the container when the latter is raised from its support.

3. Improved means for venting containers for electric batteries comprising the combination with a battery container of a tube passing through said container from top to bottom, a rod slideably mounted in said tube, a vent mounted in the top of the container to one side of the slideably operating rod, a cap for opening and closing said vent, a lever carrying said cap and operatively connected with the top of said rod, resilient means for pressing said rod downwards so that its lower end protrudes beyond the base of the container and closes the vent when the container is raised from its support and whereby said rod is pushed upwards and opens the vent when the container is raised from its support.

4. Improved means for venting containers for electric batteries comprising the combination with a battery container of a tube passing through said container from top to bottom, a rod slideably mounted in said tube, a vent mounted in the top of the container to one side of the slideable operating rod, a cap for opening and closing said vent, a resilient lever carrying said cap and operatively connected with the top of said rod so as to press the latter downwards, and so that its lower end protrudes beyond the base of the container and closes the vent when the container is raised from its support and whereby said rod is pushed upwards and

opens the vent when the container is raised from its support.

5. Improved means for venting the boxes or containers for electric batteries or accumulators comprising a vent in the top of the box or cell, adapted to be opened and closed through the medium of a rod so arranged and fitted as to be pressed upward and open the vent when the box is resting on its support and protrude from the bottom and close the vent when the box is raised from its support, an outer casing for said battery container furnished with inclined sides so arranged that the inclination of the container therein will permit the operating rod to protrude and operate to open and close the vent.

6. Improved means for venting containers for electric batteries comprising a vent in

the top of the container, a rod in operative connection with said vent for the purpose of opening and closing the same, means for mounting the rod in such manner that it is pressed upward to open the vent when the container is resting on its support and whereby said rod protrudes from the bottom of the container and closes the vent when the container is raised from its support, an outer casing for said battery container furnished with inclined sides so arranged that the inclination of the container therein will permit the operating rod to protrude and operate to open and close the vent.

In testimony whereof I have signed my name to this specification at London this 28th day of June, 1923.

WILLIAM ROWLAND EDWARDS.
